PHOTOGRAPHIC CAMERA

Hermann Claar, Kurt Steisslinger, and Ernst Lieser, all of Stuttgart-Hedelfingen, Germany, assignors to Eastman Kodak Company, Rochester, N.Y., a corporation of New Jersey

Filed June 11, 1965, Ser. No. 85,675

Claims priority, application Germany Feb. 8, 1965

Term of patent 14 years

(Cl. D61—1)

FIG. 1

FIG. 2

FIG. 3

FIG. 4

FIG. 5

FIG. 6

FIG. 1 is a top plan view of a photographic camera showing our new design with the flash reflector folded down onto the top of the camera;

FIG. 2 is a front view thereof;

FIGS. 3 and 6 are elevational views of opposite ends thereof;

FIG. 4 is a rear view thereof;

FIG. 5 is a bottom view thereof;

FIGS. 7-10 correspond to FIGS. 1, 2, 4 and 3, respectively, but show the flash reflector in a raised or operative position.

The broken-line showing of a flash lamp in FIGS. 8 and 10 is for illustrative purposes only.

We claim:

The ornamental design for a photographic camera, as shown and described.
